UNITED STATES PATENT OFFICE.

AXEL WELIN, OF LONDON, ENGLAND.

BREECH MECHANISM FOR GUNS.

SPECIFICATION forming part of Letters Patent No. 451,865, dated May 5, 1891.

Application filed July 2, 1890. Serial No. 357,479. (No model.)

To all whom it may concern:

Be it known that I, AXEL WELIN, mechanical engineer, a subject of the King of Sweden and Norway, residing at the Scandinavian

5 Sailors' Temperance Home, Garford Street, London, England, have invented certain new and useful Breech Mechanism for Guns, of which the following is a specification.

According to this invention I close the 10 breech of a gun by means of two screw-blocks, one behind the other, which engage with different screws on the gun, so that in opening and closing the breech they are rotatable at different speeds. By using two breech-blocks 15 engaging with screws of different pitches or of opposite twist a much quicker pitch can be used than with a single screw, so that the breech can be much more speedily opened and closed. One of the breech-blocks may 20 have a slow screw to afford the requisite security, while the other block, having a quick screw, gives rapidity of action.

In the accompanying drawings, illustrating 25 my invention, Figure 1 is a rear elevation of a gun constructed according to my invention, the breech being open. Fig. 2 is a longitudinal section, (on the line 1 1, Fig. 1,) the breech being closed. Fig. 3 is a longitudinal section of the gun with the breech-blocks and mechanism connected therewith removed. Fig. 4 is a rear elevation, Fig. 6 a front elevation, and Fig. 5 a longitudinal section, (on the line 2 2, Figs. 4 and 6,) of the breech-block carrier. Fig. 7 is a rear elevation, Fig. 9 a front elevation, Fig. 8 a longitudinal section, (on the line 3 3, Figs. 7 and 9,) and Fig. 10 a side elevation, of the rear breech-block; Fig. 11, a rear elevation, Fig. 13 a front elevation, Fig. 12 a longitudinal section, (on the line 4 4, Figs. 11 and 13,) and Fig. 14 a side elevation, of the front breech-block. Figs. 15 and 16 are a front view and plan of the firing-pin. Figs. 17 and 18 are detail views of the firing-pin and its operating mechanism. Fig. 19 is 45 a detail view showing particularly the firing-pin and the devices in the front breech-block for operating it, and Fig. 20 is a perspective view of the rear breech-block and the firing-pin.

50 A is the rear breech-block. Its periphery is furnished with a divided screw *a* of an ordinary type, which engages with a correspond-

ing slow screw *a'* on the inside of the breech of the gun in the usual manner. As shown, there are a number of screw-segments with 55 inclined edges.

B is the front breech-block, whose periphery is furnished with a quick-threaded screw *b*², which engages with a corresponding screw *b'* upon the inside of the breech of the gun. 6c The pitch of this quick-threaded screw is the same as that of the inclined edges of the screw-segments on the block A. The two blocks are connected together by means of a dovetailed projection A' upon the block A, 65 which engages with a corresponding recess *b*³ in the block B. The projection A' is in the form of a ring, two opposite quadrants of which have a rectangular section, while the other two quadrants are undercut. (See Figs. 70 8 and 9.) The groove *b*³ in the block B is formed in a corresponding manner, as shown in Figs. 11 and 12, so that when the two blocks are put together and one of them turned they are locked together. The block 75 B has a semicircular overhanging lip B', which takes hold of the rim of the cartridge and acts as an extractor. The block A carries at its rear a hollow stem A², which passes out through the breech-block carrier C, as 80 shown in Fig. 2. The stem A² has longitudinal grooves *d* upon it to receive projections D' on the handle D, so that when the handle is turned the block A turns with it, but is also free to move longitudinally along 85 its axis. The breech-block carrier C has an overhanging lip C' at its rear to keep the handle D in place, and it has fixed to it projections C², which slide in guides E E upon the rear of the gun. Its inside is furnished 90 with helical or inclined lugs or ribs C³, which enter grooves A³ in the breech-block A. When a cartridge is put into the open breech, it cannot at first be rammed home, as the top and bottom of its rim come against the projections 95 C², which hold it in exactly the right position to allow the semicircular lip B' (shown in dotted lines in Fig. 1) to come beneath it. When the breech-blocks are inserted and locked in the breech, the cartridge is held in 100 position, as shown in Fig. 2, the lip B' engaging with the rim of the cartridge, ready to extract it when the breech-blocks are withdrawn. The firing-pin F and its spring f are

contained in the hollow stem of the handle D. The firing-pin is provided with a lug F', which rides upon an incline G in a recess at the rear end of the block B. When the firing-
5 pin is in its forward position, it cannot turn relatively to the block A, as the projection F' fits in the slot H; but this slot is widened at its rear, so that when the firing-pin is drawn back it can turn slightly relatively to the
10 block A, and when so turned is caught by the shoulder H' in the slot H and is retained in the cocked position.

When the gun has been fired, the front end of the lug F' lies in the notch G², while the
15 main body of the lug lies in the slot H in the front of the stem of the block A, in which it is held and prevented from turning, so that when the block is turned to open the breech the end of the lug F' rides up the incline G,
20 thus drawing back the firing-pin and cocking the gun. When the lug F' has been drawn back clear of the slot H, the continued rotation of the block B carries the lug around and lodges it on the shoulder H'.

25 The action of the apparatus is as follows: In order to open the breech after the gun has been fired, the handle D is turned, thereby turning the breech-block A, causing the segments of its divided screw to disengage from
30 the corresponding divided screw in the breech of the gun. This turning motion at the same time to a slight extent withdraws the block A from the breech, carrying the block B with it, which, through its overhanging lip B', starts
35 the empty cartridge-case. The turning of the block A relatively to the block B causes the lug F' on the firing-pin F to ride up the incline G and so cocks the gun. At the moment the divided screw on the breech-block B has
40 been disengaged from the divided screw in the breech the lug F' has reached the top of the incline and has passed onto the shoulder H' and comes against side abutments on the blocks A and B, preventing the block A from
45 rotating independently of the block B, so that as the handle is continued to be turned the two blocks are rotated together. The effect of this is that the block B, by reason of its quick-threaded screw, has a rapid rearward
50 motion imparted to it, and the block A moves with it, which it is free to do as the pitch of the screw-thread upon the block B is the same as that of the helical spaces between the screw-segments on the block A. When the two
55 blocks have been fully withdrawn into the carrier C, the latter, with the blocks, is caused to slide to one side along the guides E into the position shown in Fig. 1. The empty cartridge-case is then removed, a fresh cartridge
60 is put in, and the breech closed by reversing the movements above described. When the two blocks are nearly home, the screw-threads on the block A engage with the corresponding threads in the gun, and the block A now
65 turns faster than the block B, the latter being forced home by the longitudinal thrust of the former. During this motion the lug F' is re-

tained in the notch H' and is turned clear of the incline G in the block B, so that it is free to be forced forward by its spring and fire 70 the gun when it is pushed off H'.

The gun is fired by the line K, which pulls the slide L, having an inclined slot l. This gives endwise movement to the rods M and M', which push the lug F' off the shoulder H'.
75 The firing-pin is then operated by its spring f in the usual way.

What I claim is—

1. In breech mechanism for guns, the combination of two breech-blocks connected together, one behind the other, rotatable at different speeds, and engaging with the breech of the gun. 80

2. In breech mechanism for guns, the combination of two breech-blocks connected together, one behind the other, and means for rotating them at different speeds while being simultaneously withdrawn from the gun. 85

3. In breech mechanism for guns, the combination of two breech-blocks connected together, one behind the other, and having screws of different pitch engaging corresponding screws in the gun, and means for operating the breech-blocks. 90

4. In breech mechanism for guns, the combination of two breech-blocks, one behind the other, rotatable at different speeds and connected to move longitudinally together, and means for withdrawing the blocks from the breech of the gun. 95

5. In breech mechanism for guns, the combination of two breech-blocks connected together, one behind the other, one having a quick screw and the other a slow divided screw and both engaging corresponding screws in the gun. 105

6. In breech mechanism for guns, the combination of two breech-blocks connected together, one behind the other, one having a slow screw and the other a quick divided screw and both blocks engaging corresponding screws in the gun, the pitch of the slow screw on the breech-block corresponding with the pitch of the inclined edges of the screw-segments of the divided screw in the gun. 110

7. In breech mechanism for guns, the combination of two breech-blocks connected together, one behind the other, rotatable at different speeds and engaging with the breech of the gun, a breech-block carrier to receive the blocks when withdrawn, and means for operating the carrier. 120

8. In breech mechanism for guns, the combination of two breech-blocks connected together, one behind the other, and having screws of different pitch engaging corresponding screws in the gun, a breech-block carrier to receive the blocks when they are withdrawn from the gun, and means for operating the breech-blocks and carrier. 125

9. In breech mechanism for guns, the combination of two breech-blocks connected together, one behind the other, rotatable at different speeds and engaging with the breech

of the gun, a handle connected with the rear breech-block to rotate it, and means for connecting the rear breech-block to the handle to permit the former to move longitudinally relatively thereto.

5 10. In breech mechanism for guns, the combination of two breech-blocks, one behind the other, connected together, which engage different screws in the gun and rotate at different speeds, a breech-block carrier to receive

the blocks when withdrawn, a handle, with relation to which the breech-blocks move longitudinally, and connections between this handle and the breech-blocks.
